ALBERT THOMPSON, OF RIDGWAY, PENNSYLVANIA.

Letters Patent No. 77,128, dated April 21, 1868.

IMPROVEMENT IN SHINGLE-MACHINES.

The Schedule referred to in these Letters Patent and making part of the same.

TO ALL WHOM IT MAY CONCERN:

Be it known that I, ALBERT THOMPSON, of Ridgway, in the county of Elk, and State of Pennsylvania, have invented a new and improved Shingle-Machine; and I do hereby declare that the following is a full, clear, and exact description of the construction and operation of the same, reference being had to the annexed drawings, making a part of this specification, in which—

Figure 1 is a longitudinal vertical section.

Figure 2 is a similar section of the carriage through the line $x x$ of fig. 3.

Figure 3 is a plan.

Figure 4 is a side elevation of the wheels detached.

In this invention the carriages are attached by a new device, by means of which one of them can be detached and stopped, for adjusting the bolt, without interfering with the action of the other. The heading and pointing are also regulated by a new mechanical arrangement, and a new apparatus is employed for adjusting the speed of the carriages.

In the drawings, A represents the wooden framework of the machine; B is the saw-mandrel; B¹ a tapering or conical vertical pulley on the saw-mandrel; C, a similar pulley, tapering in the opposite direction, and standing near the end of the machine; B², a belt connecting the pulleys B¹ and C; D, a vertical shaft at the end of the machine, receiving motion from the pulley C by means of gearing, c¹ c², and communicating said motion, by other gearing, c² c³, to a horizontal shaft, E, extending across the end of the machine; and F F wheels, running on the ends of the shaft E, and each carrying a horizontal pitman, G G, by which the carriages, I I, are caused to slide back and forth over the horizontal saw H.

The carriages run on slide-bars, K K, and are drawn back and forth by being attached to a beam, L, which extends across the machine from one slide-bar to the other, and itself slides on the bars in the same direction, as the carriages, being actuated by the pitmen which are connected with its extremities; or the pitmen may be each connected with sliding blocks, J J, running on the slide-bars on each side of the machine, and the ends of the beam L may be fastened firmly to these blocks. The latter is the method of construction shown in the drawings.

The means for attaching the carriages to the beam, L, which draws them back and forth, is as follows: Between two small horizontal metallic plates are two barbed dogs, m m, pivoted at their middle, and having a spring, m¹, to draw their heads together, and a cord, m², by which, by means of a spindle and hand-wheel, the ends opposite to the heads may, at pleasure, be drawn together, and the heads thrown apart. Corresponding to these dogs, is a double-barbed coupling-bolt, m³, with bevelled head, fixed to the side of the carriage, so that when the carriage and the beam L come together, the bevelled head, m³, will enter between the dogs m m, and push them apart, until the bars or shoulders on the sides of the bolt catch behind the teeth of the dogs, when the carriage will be firmly attached to the sliding beam, and will be drawn back and forth by it. By giving the hand-wheel a turn, the dogs may be thrown apart, and the carriage liberated from the sliding beam. Each carriage is provided with this arrangement, so that either may at any time be detached from the running-apparatus, and held at the end of the machine, at pleasure, for the purpose of changing or adjusting the bolts.

The bolt is held between two shafts, N N', each provided with a series of spur-wheels, n n n, which prevent the bolt from slipping down between the shafts any faster than the rotation of the shafts is designed to allow it to move. One shaft, N', is fixed in position, the other, N, bears in a sliding frame, O, which slides from the end towards the centre of the carriage, or *vice versa*, being impelled towards the middle of the carriage by springs, o o, and a little shaft, P, connected with the sliding frame by a cord, or by a spur-wheel gearing into a rack on the frame, being provided for the purpose of enabling the operator to retract the shaft N when he desires to take out the old bolt or put a new one in.

The rotation of the shafts N N', which hold the bolts, is so adjusted, that at every alternate return of the carriage, one shaft moves farther round than the other, and drops its end of the bolt farther, forming the head

of the shingle, while the point is formed at the other end of the bolt; and, at the next return of the carriage, the operation is reversed, and the point formed at the end of the bolt where the head was formed before.

In order to make the shafts rotate in this manner, they are both put in motion by a single shaft, R, by means of cam-wheels S S', on said shaft, gearing into and turning spur-wheels n' n', on the end of the shafts N N'. The form and arrangement of the cams on the cam-wheels are shown clearly at s x s x s s, in figs. 2 and 4. The spurs 1, 2, 3, 4, 5, 6, 7, 8, 9, 0, on the spur-wheels n' n', are arranged at different distances apart, the distance from 1 to 2 being so little that if the cam s run between those spurs, the shafts N N' will be turned only far enough to form the point of the shingle, but if the cam run between the spurs 2 and 3, the shaft will turn far enough to form the head of the shingle. A lever, T, pivoted on the shaft R, and having a weighted hand, t, to keep it in position, at each return of the carriage to the end of the machine, strikes against or runs under a staple, T', throwing the head of the lever up, and causing it to partially rotate the shaft R by means of a dog, t', on its side, working in a ratchet-wheel, T', attached to the shaft. The parts are so constructed, that the rotation thus imparted to the shaft R is just sufficient to cause one of the cams, s, to operate through its whole length on the spur-wheel, n', leaving the next return of the carriage to operate the next cam, and so on. And the cams are so adjusted to the spurs of the wheels n' n', that one cam will run its whole length between two spurs, as, for instance, those numbered 1 and 2, and then the next cam will catch between the next two, 2 and 3, and so on indefinitely. By this means every successive return of the carriage to the end of the machine sets the bolt for a new cut, adjusting it so that the shingles are headed and pointed with perfect accuracy at both ends of the bolt.

In order to accommodate one of the cam-wheels to the sliding shaft N, I make the cam-wheel itself movable along the shaft that carries it, cutting a bead in the shaft and in central aperture of the wheel to prevent the turning of the latter on its shaft, and extending an arm, v, from the sliding frame O to the side of the cam-wheel, where it may be looped around the shaft R to hold it more steadily. In this way the cam-wheel will be held between the arm v, and the spur-wheel n', in whatever direction the frame O and shaft N may be moved, and will thus be always kept in the proper connection with the spur-wheel which it is designed to actuate.

The speed with which the carriages will move is regulated by means of the two conical pulleys, B' C. By sliding the belt up to the top of the pulleys, the speed of the carriages will be increased, and by sliding it down diminished. In order to adjust the belt more readily, I cause it to pass through a slotted plate, p, held at the end of an arm or pair of arms, a, projecting from a rock-shaft, W, which extends across the machine under the saw, and which can be partially rotated by a lever, W', at the side of the machine, connected with a crank, w, on the end of the rock-shaft by a rod, w'. By throwing the handle of this lever back and forth, the slotted plate p is raised or depressed, carrying the belt B' up or down with it.

Q is a lever, by which the spur-wheels c c' may be thrown out of gear, in order to stop the motion of both carriages at once.

Having thus described my invention, what I claim as new, and desire to secure by Letters Patent, is—

1. I claim the combination of the carriages I I', having the barbed coupling-bolt m³, with the barbed dogs m m, spring m¹, and cord and pulley m², by which either of the carriages can, independently of the other, be instantly attached to or detached from the sliding beam L which operates them.

2. I claim the combination of the cam-wheels S, having the cams s s s s formed and operating in the manner described, with the shaft N, having the spur-wheels n' n', the spurs of which are at different distances apart, the whole operating together in the manner and for the purposes set forth.

To the above specification of my invention I have signed my hand, this 6th day of February, 1868.

ALBERT THOMPSON.
